US0D1003418S

(12) **United States Design Patent** (10) **Patent No.:** **US D1,003,418 S**
(45) **Date of Patent:** **** Oct. 31, 2023**

(54) **CAMPING FAN**

(71) Applicant: **Mambate US Inc.**, Brooklyn, NY (US)

(72) Inventor: **Shuijiao Zhang**, Brooklyn, NY (US)

(73) Assignee: **Mambate US Inc.**

(**) Term: **15 Years**

(21) Appl. No.: **29/880,978**

(22) Filed: **Jul. 30, 2023**

(51) **LOC (14) Cl.** **23-04**

(52) **U.S. Cl.**

USPC **D23/370**

(58) **Field of Classification Search**

USPC D23/314, 335, 328, 332, 370-379,
D23/381-385, 411-414, 360

Primary Examiner — Keith J Wilson

(57) **CLAIM**

The ornamental design for a camping fan, as shown and described.

DESCRIPTION

FIG. 1 is a top, front, right side perspective view of a camping fan, showing my new design;
FIG. 2 is a top, rear, right side perspective view thereof;
FIG. 3 is a front elevational view thereof;
FIG. 4 is a rear elevational view thereof;
FIG. 5 is a left side elevational view thereof;
FIG. 6 is a right side elevational view thereof;
FIG. 7 is a top plan view thereof;
FIG. 8 is a bottom plan view thereof; and,
FIG. 9 is an alternative perspective view of the camping cookware when is used.

1 Claim, 9 Drawing Sheets
